UNITED STATES PATENT OFFICE.

JOHANNES WIRTH, OF HAMBURG, GERMANY.

DESIGN FOR AN INDICATOR FOR BAROMETER.

Application filed December 11, 1923. Serial No. 7,992. Term of patent 14 years.

To all whom it may concern:

Be it known that I, JOHANNES WIRTH, a citizen of Germany, residing at Hamburg, Republic of Germany, have invented a new, original, and ornamental Design for Indicator for Barometer, of which the following is a specification, reference being had to the accompanying drawing, forming part thereof.

The figure is a face view of an indicator for barometer, showing my new design.

I claim:

The ornamental design for an indicator for barometer substantially as shown and described.

JOHANNES WIRTH.
